US0D1054252S

(12) United States Design Patent (10) Patent No.: US D1,054,252 S
(45) Date of Patent:  Dec. 17, 2024

(54) TUMBLER

(71) Applicant: PI-Design AG, Baar (CH)

(72) Inventor: Jorgen Bodum, Meggen (CH)

(73) Assignee: Pi-Design AG, Triengen (CH)

() Term: 15 Years

(21) Appl. No.: 29/877,756

(22) Filed: Jun. 12, 2023

(30) Foreign Application Priority Data

Dec. 16, 2022 (WO) WIPO126500

(51) LOC (14) Cl. 07-01

(52) U.S. Cl.

USPC D7/523
